UNITED STATES PATENT OFFICE

SAMSON BORGNIS, OF OLNEY, PENNSYLVANIA

GARTER GRIP

Application filed May 21, 1930. Serial No. 454,217.

My invention relates to new and useful improvements in a garter grip and has for one of its objects to improve the structure shown and described in my prior Patent No. 1,586,-
5 401, dated May 25, 1926.

Another object of the invention is to provide a socket member of a garter grip having an unique construction whereby it may be readily removed from the stud member of
10 the grip when it is desired to separate them.

Another object of the invention is to provide a socket member having a garter grip including a housing open from end to end and so fashioned as to provide a recess for
15 the resilient clip or clamp of peculiar arrangement.

A still further object of the invention is to provide a novel means for clamping the stud member to the garter pad whereby the
20 hole or holes formed by the fastening means will be covered at all times.

With these ends in view, this invention consists in the details of construction and combination of elements hereinafter set forth
25 and then specifically designated by the claims.

In order that those skilled in the art to which this invention appertains may understand how to make and use the same, I will describe its construction in detail, referring
30 by numerals to the accompanying drawings forming a part of this application, in which:—

Fig. 1 is a front elevation of a garter illustrating my improved garter grip applied thereto.

Fig. 2 is an enlarged plan view of the socket member of the grip.

Fig. 3 is a section on the line 3—3 of Fig. 4.

Fig. 4 is a section on the line 4—4 of Fig. 3.

Fig. 5 is a plan view of the stud member prior to the plate being bent into shape.

Fig. 6 is an edge view of the stud member after being fashioned ready for attachment to a garter with a portion of the plate broken away and shown in section.

In carrying out my invention as herein embodied, 10 represents a garter of any well known or desired construction including a pad 11 provided with the usual clasp 12 for attachment to a hose and a strap 13 usually

of elastic material with its fore end looped and provided with an attaching buckle 14, the latter being used for adjusting the size of the garter.

To the pad 11 is secured a stud member 15 of my improved garter grip by means of prongs 16 which are formed as integral parts of the plate 17 and have barbs 18 produced by partially severing sections of metal from the prongs and bending them outward as shown in Fig. 6.

The prongs 16 are bent back under the plate and then outward or downward as shown in Fig. 6 so that the working parts of the prongs underlie the plate and are spaced some distance from the rear edge thereof.

In actual practice, these prongs are projected through the pad 11 or the facing element thereof and then bent up toward the under side of the plate in order to clamp said stud element on the pad. By this arrangement, the holes formed in the pad or facing element thereof will underlie the plate 17 and therefore if the material is stretched so as to open the holes, they will still be invisible. The stud 19 has a reduced neck 20 and is also provided with a shank 21 which is projected through the plate and headed for riveting the stud to the plate.

A socket member 22 is attached to the fore looped end of the strap 13 by threading said strap through the slot 23 in the plate 24, said plate having an aperture 25 therethrough. This plate carries a housing 26 which surrounds the aperture 25 and spaced from the edge thereof so as to form the inner end wall of the housing while the outer end of said housing is provided with an aperture 27 approximately corresponding in size to the aperture 25.

Within the housing is located the resilient clip or clamp 28 formed from a section of suitable gage spring-wire and fashioned to provide a bow 29 from which project the legs 30 and 31, the former terminating in an arcuate section 32 and the terminal of the latter lies adjacent the terminal of the leg 31. The legs 30 and 31 diverge from the bow 29 as shown in Fig. 3 so that at the end of the clamp opposite the bow 29, said legs are separated

further apart than adjacent the bow and being free may be readily disengaged from the stud member by a simple tilting of the socket member so that the open end of the clamp first rides over the head of the stud.

5 In practice, the socket member is placed over the stud until the aperture 25 registers with said stud and then by pressing the two together the resilient clamp will be forced over the stud through the separation of the 10 legs of said clamp, but as soon as the socket member has reached a certain position, the legs of the clamp will contract or enter the neck 20 and thereafter prevent accidental dis- 15 placement of the socket member from the stud member.

Of course I do not wish to be limited to the exact details of construction as herein shown, as these may be varied within the limits of 20 the appended claims without departing from the spirit of my invention.

Having thus fully described my invention, what I claim as new and useful is:—

1. A garter grip comprising stud and 25 socket members, said stud member including a plate, prongs projecting from said plate and underlying the body thereof, barbs projecting from said prongs and a stud riveted to said plate, and said socket member includ- 30 ing an apertured plate, a housing mounted on said plate and surrounding the aperture therein, said housing having an aperture in its outer end and a spring clamp within said housing formed from a piece of wire fash- 35 ioned to produce a bow, diverging legs projecting from said bow and one of said legs having an arcuate terminal.

2. A garter grip comprising a stud member and a socket member, the latter includ- 40 ing a plate, a housing thereon, said housing and plate having aligned apertures therein and a spring clamp mounted within said housing and including a bow, diverging legs projecting from said bow and an arcuate portion formed with the end of one of said legs.

45 3. A garter grip comprising stud and socket members, said stud member including a plate, a stud carried by said plate, prongs formed integral with the plate and bent back 50 upon said plate and then outward whereby said prongs underlie the plate a distance from the edges thereof, and barbs carried by the prongs and projecting from the faces of said prongs which are bent toward the plate when the stud member is in use.

55 In testimony whereof, I have hereunto affixed my signature.

SAMSON BORGNISS.
